(57) **CLAIM**

The ornamental design for a handle for a vaporizer, as shown and described.

DESCRIPTION

FIG. 1 is a perspective view of a handle for a vaporizer, showing my new design;

FIG. 2 is a left elevational view of the handle for a vaporizer of FIG. 1;

FIG. 3 is a front elevational view of the handle for a vaporizer of FIG. 1;

FIG. 4 is a right elevational view of the handle for a vaporizer of FIG. 1;

FIG. 5 is a back elevational view of the handle for a vaporizer of FIG. 1;

FIG. 6 is a top plan view of the handle for a vaporizer of FIG. 1;

FIG. 7 is a bottom plan view of the handle for a vaporizer of FIG. 1;

FIG. 8 is a perspective view of a second embodiment for a handle for a vaporizer, showing my new design;

FIG. 9 is a right elevational view of the handle for a vaporizer of FIG. 8;

FIG. 10 is a front elevational view of the handle for a vaporizer of FIG. 8;

FIG. 11 is a left elevational view of the handle for a vaporizer of FIG. 8;

FIG. 12 is a back elevational view of the handle for a vaporizer of FIG. 8;

FIG. 13 is a top plan view of the handle for a vaporizer of FIG. 8; and,

FIG. 14 is a bottom plan view of the handle for a vaporizer of FIG. 8.

(Continued)

The broken line showing is for purposes of illustrating portions of the handle for a vaporizer that forms no part of the claimed design.

1 Claim, 2 Drawing Sheets
